UNITED STATES PATENT OFFICE.

MARTIN NYSTROM, OF CHICAGO, ILLINOIS, ASSIGNOR TO THE BRUNSWICK-BALKE-COLLENDER CO., OF CHICAGO, ILLINOIS, A CORPORATION OF DELAWARE.

DESIGN FOR A LOUD-SPEAKER CABINET.

Application filed September 14, 1928. Serial No. 28,144. Term of patent 7 years.

To all whom it may concern:

Be it known that I, MARTIN NYSTROM, a citizen of the United States, residing at Chicago, in the county of Cook and State of Illinois, have invented a new, original, and ornamental Design for Loud-Speaker Cabinets, of which the following is a specification, reference being had to the accompanying drawing, forming part hereof.

The figure is a perspective view of a loud-speaker cabinet embodying my invention.

I claim:

The ornamental design for a loud-speaker cabinet substantially as shown.

In testimony whereof I hereunto subscribe my name.

MARTIN NYSTROM.
